United States Patent

Des. 238,979
Patented Feb. 24, 1976

238,979

CONTAINER FOR PERSONAL BREATHING APPARATUS

Eugene N. Perry, Sunnyvale, and Orval D. Feldman, Campbell, Calif., assignors to Lockheed Missiles & Space Company, Inc., Sunnyvale, Calif.

Filed Dec. 23, 1974, Ser. No. 535,516

Term of patent 14 years

Int. Cl. D3—02; D24—02
U.S. Cl. D87—1 R

FIG. 1

FIG. 3

FIG. 4

FIG. 5

FIG. 6

FIG. 1 is a perspective view of a container for personal breathing apparatus,

FIG. 2 is a top plan view,

FIG. 3 is a left end elevational view with the right end elevation being substantially a mere image thereof,

FIG. 4 is a front elevational view,

FIG. 5 is a rear elevational view, and

FIG. 6 is a bottom plan view.

We claim:

The ornamental design for a container for personal breathing apparatus, as shown and described.
